UNITED STATES PATENT OFFICE.

EDWARD SAMUEL BOND, OF BIRMINGHAM, COUNTY OF WARWICK, ENGLAND.

WIRE-NETTING MACHINE.

SPECIFICATION forming part of Letters Patent No. 432,223, dated July 15, 1890.

Application filed February 12, 1889. Serial No. 299,672. (No model.)

To all whom it may concern:

Be it known that I, EDWARD SAMUEL BOND, engineer and machinist, of the Crown Engine and Machine Works, Lower Hurst Street East, 5 Birmingham, in the county of Warwick, England, and a subject of Great Britain, have invented certain new and useful Improvements in Machinery for Manufacturing Wire-Netting; and I do hereby declare that the following is a sufficient description of the invention to enable those skilled in the art to which it appertains to carry the same into practical effect.

My invention has for its object improvements in machinery for manufacturing wire-netting, and relates more particularly to the driving-gear or the means of operating the plates and pinions for twisting the wire. These plates have hitherto been operated in a very clumsy and noisy manner, which has prevented the machines being driven any other than slowly, as any jerking throws the wearing parts into more or less disorder.

Now my improved machinery is very simple, and I am therefore able without risk to run the machines at, say, above twice the speed which has hitherto been possible. This is of course a most important advantage, as a machine having my improvements can be utilized to do the same amount of work as two of the ordinary kind in the same amount of time and with a saving of cost, as well as in attendance and the space occupied, while the netting is manufactured in a much more efficient manner, by reason of there being little or no vibration in the working of the machine. Thus less capital is required to produce the work.

My improvements further consist in the use of a rack in each half of the plates instead of one in the one-half, thereby increasing the power of the pinions for twisting stronger gages of wire and at the same time also preventing the pinions from slipping out of gear, which is an important failing with the present machines.

Another portion of my invention consists in the support of the plates by means of the stretchers being provided with flanges which receive the plates, thereby preventing them from bending in the center, also keeping them true on their edge, and by these means allow-

ing the use of a machine of any length which may be required.

These improvements, combined with the improved arrangement for the perfect adjustment of the plate-racks and various parts, form a most cheap and compact machine, which is thoroughly effective in its working.

In order that my invention may be clearly understood and more easily carried into practice, I have appended hereunto various sheets of drawings, upon which I have illustrated enough of the ordinary parts of a wire-netting machine to show the application of my improvements thereto.

Figure 1 is a plan of both ends of the machine, the right-hand side showing the top plates C and the left-hand side showing a sectional plan of the racks D, with their connections. Fig. 2 is a perspective view of the driving end of the machine with a portion of the frame-work broken away, so as to show the bevel cam-wheel A in gear with the driving bevel-wheel F', and the mode of operating the plates C. Fig. 3 is a broken-off elevation from the rear of the machine to show the driving-shaft F and bevel-wheel F' and the action of the internal cam-groove α^3 . Fig. 4 is an enlarged elevation of the center or working portion of the machine broken away in the middle, but showing the twisting of the wire, one of the tubes 2^a being in section. Fig. 5 is a cross-section through the last figure, also showing the tube broken away to show the coil, as hereinafter explained. Fig. 6 is an enlarged sectional plan through the plates, showing the racks and pinions. Fig. 7 is an elevation of the disk A and part of the connecting-rod D', hereinafter described. Fig. 8 is a plan of the attachment N of the lever M to the plates C. Fig. 9 is a side elevation of the same. Fig. 10 is a plan of the adjustable pivoted arms B for operating the plates C. Fig. 11 is a view of the ends of the plates C, showing a modification of the method of working them.

The top and bottom plates C, racks D, and pinions E are similar to those in the ordinary wire-netting machine and operate upon the wire in a similar manner, as shown in Figs. 4 and 5—i. e., one half of the plates C slide horizontally backward and forward by means described hereinafter in the reverse direction

to the other half, which also slide backward and forward, and between these two plates C the half-pinions E are mounted to revolve, and between the top and bottom halves of each of the pinions E the removable tubes 2^a are fixed to revolve with the said half-pinions. Within the tubes are placed the coils of wire 2^d, the end of which passes up through the hole in the halves E^c of the pinion and which forms the one strand of the netting, the other strand 3^b passing up from the spindles 3^a, round the roller 5, through the halves E of the bottom pinion, then up between the tubes 2^a, and through the halves E^b of the top pinions, the relative halves of the pinions being altered with regard to each other at each move of the plates C, E^c being at one time opposite E^d, as shown at Fig. 6, and another time opposite E^e, and after each change both halves are revolved together by means of a sliding backward-and-forward motion of the toothed racks D, which are operated as hereinafter described, and which engage in the teeth e' in the pinions E^a and E^b. By these means the wire is twisted and spread, merely forming the wire-netting, as shown by Fig. 4, which is drawn away as formed by means of the projections 4^b upon the cylinder 4^c, which is mounted and revolves between the ends Y and Z of the machine.

Now my improvements relate, first, to the operation of the plates C, so as to obviate the use of any stops to the said plates, which I effect as follows: I mount the disk A upon any convenient part of the machine, but preferably upon the brackets A' and A², which may be cast in one with the end Z of the machine. The disk A is formed as a bevel-wheel, so as to engage and receive its motion from the bevel-wheel F' on the main shaft F. Upon the face of the disk the internal cam or groove a³ is formed, which actuates the roller or stud h' on the lever H, which, as it rises and falls, slightly revolves the small shaft H² in the bearings h⁴ and h⁵, and by means of the toothed segment H³, engaging with the toothed segment K', the vertical shaft K revolves in the bearings K² and K³, which are formed on the end frame Z of the machine. The cross-arms B are fixed to the bottom and top of this shaft and are connected to the upper and lower plates C by means of the link M and attachment N, (shown by Figs. 8 and 9,) thereby operating the plates C in the reverse direction to each other, as required.

To prevent the slightest spring or vibration occurring to throw the plates out of position, I provide the stops h⁶ and h⁷ to the lever H, which may be adjusted to secure it at the extremes of the stroke, thereby locking the lever between the stops and the edge of the groove a³.

I do not confine myself to the particular position of the internal cam and disk A, as I may place it horizontally, in which case the connection with the shaft K would be direct. It will also be obvious that the plates C may be

operated with a similar effect by a double eccentric or the two eccentrics mounted upon the shaft R', as shown in Fig. 11. To allow of the most perfect adjustment of the plates C with regard to each other, the arrangement shown by Fig. 10 is provided, the arms B having the slots b⁵, in which the loose pieces b' are inserted. These pieces b' are provided with the inclined projections b², which butt against similar inclines formed in the side of the slots b⁵ in the arms. The set-screws b³ are provided for adjusting the position of the loose pieces b', and Fig. 10 shows on each side of the arm the difference in the position of the pin b⁴ at the two extremes of adjustment. Further adjustment may be obtained by the arrangement shown by N, Figs. 8 and 9, which is for the purpose of attaching the link M to the plates C, the pin n', to which the link M is secured, being made to move in the slot n² and is afterward firmly secured in position by the set-screws n³. This arrangement is also used for the adjustment of the racks D. The racks D are operated at the reverse end of the machine and from the other side of the disk A by means of the connecting-rod D', which is connected to the vertical shaft O and in turn to the racks D by the arms P and smaller connecting-rods P' in a similar way to the operation of the plates C; but in operating both of the racks D backward and forward, as shown, instead of only one, as heretofore, it will readily be seen that as the half-pinions E alter their relative positions with regard to each other at each stroke of the racks, and that the end halves e² or e³ at each stroke have no corresponding half-pinions opposite to them to allow them to revolve, they cannot when in such position be actuated by the movement of the rack. The independent movement of the racks is, however, allowed by means of cutting away the two teeth of the long half-pinion e² at one end and the short half-pinion e³ at the other end, so as to allow the racks D to move independently when these half-pinions are not able to revolve by reason of not being in the solid part of the plate, as seen by e³, Fig. 1; but as soon as the half-pinion e³ returns opposite the next half of the pinion it forms a circle in which it can and does revolve by means of the other half, which is provided with teeth and is actuated by the other rack D. I am thus enabled to work the pinions E with double racks, thereby obtaining increased strength for the manipulation of a thicker strand of wire; but I do not confine myself to using any particular number of racks in the upper or lower parts or this particular mode of operating the racks, in combination with the other parts of my invention. The arms P are provided with the slots P² for the further adjustment of the racks.

My improvements relate, further, to the construction of the stretchers T, for connecting the ends of the machine together, which I provide with the flange S, for the purpose of supporting the plates C and preventing them

from bending in the center. The stretchers T on each side of the plates by this means form a trough, in which the plates slide, thereby enabling me to make the machines of any desired length without fear of the plates bending downward in the middle, which at the same time keeps the plates true on their edge, thereby insuring the free and easy working of the pinions E.

10 Having now particularly described and ascertained the nature of my said invention and in what manner the same is to be performed, I declare that what I claim is—

15 1. In combination with a pair of reciprocating plates, a pair of racks attached to said plates and having their teeth facing each other, the rack-operating devices consisting of disk A, connecting-rod D', shaft O, arms P, and connecting-rods P', and a set of half-pi-
20 onions arranged between the said racks to engage them, the end half-pinions e^2 e^3 being mutilated, substantially as and for the purpose set forth.

25 2. In wire-netting machinery, the combination of the reciprocating plates and wire-twisting pinions with connections between them, and the actuating devices for said plates,

consisting of a disk having an internal cam a^3 , a lever H, engaging therewith, a shaft H², operated by said lever, and the toothed seg- 30 ments H³ and K', the vertical shaft K, the arms B, and the link M, connecting said shaft and plates, substantially as set forth.

3. In combination with the wire-twisting pinions of a wire-netting machine and the 35 reciprocating plates and connecting devices whereby said pinions are operated, adjusting-screws and loose blocks for regulating the position of said plates, substantially as set forth. 40

4. In combination with the wire-twisting pinions, reciprocating plates, and intervening connections forming parts of a wire-netting machine, a link M, pin n', slotted piece N, and screws n^3 for additional adjustment of 45 said plates, substantially as set forth.

In testimony that I claim the foregoing as my own I affix my name in the presence of two witnesses.

EDWARD SAMUEL BOND.
